[57] CLAIM

The ornamental design for an endless track wheel
guide, as shown and described.

DESCRIPTION

FIG. 1 is a side elevational view of the endless track
wheel guide embodying my new design.

FIG. 2 is a top plan view thereof.

FIG. 3 is a bottom plan view thereof.

FIG. 4 is an opposite side elevational view thereof.

FIG. 5 is a right end elevational view thereof.

FIG. 6 is a left end elevational view thereof.

FIG. 7 is a perspective view thereof.
